UNITED STATES PATENT OFFICE.

WILHELM PENZOLD, OF HANOVER, GERMANY, ASSIGNOR TO WIDERSTAND AKTIEN-
GESELLSCHAFT FÜR ELEKTRO-WÄRME-TECHNIK, OF HANOVER, GERMANY, A COM-
PANY OF GERMANY.

ELECTRICAL LIQUID HEATER.

Application filed May 22, 1922. Serial No. 562,731.

To all whom it may concern:

Be it known that I, WILHELM PENZOLD, a citizen of Germany, and a resident of Hanover, Germany, have invented certain new and useful Improvements in Electrical Liquid Heaters, of which the following is a specification.

This invention relates to electrical liquid heaters wherein the liquid constitutes a resistance and is applicable to water heaters or steam generators.

In order that the invention may be more clearly understood reference will be herein-after made to the accompanying drawings wherein Fig. 1 is a diagram illustrating a known type of electric heater; Fig. 2 illustrates one example of my invention in cross-section with accompanying diagram and Fig. 3 is a vertical sectional view of Fig. 2.

In the concentric arrangement of two metallic cylindrical electrodes as in Fig. 1 and as adopted in electric water heaters or steam generators, the current flows in a radial direction from the inner to the outer cylinder, as indicated by the dotted lines. The maximum current density and consequent maximum voltage drop occurs on the surface of the inner cylinder. The hyperbolic curve of volts per centimeter in Fig. 1 shows the variation of the voltage drop as the distance increases from the inner cylinder. These values apply where the radius of the inner cylinder $r' = 1$ cm., the ratio of the radius of the outer cylinder, r^2 , to the radius of the inner cylinder, $r' = 5$

and the voltage difference between the two electrodes is 500 volts. It will be apparent that in the concentric arrangement, the space between the cylinders is not economically utilized. In the water heater or steam generator this space is occupied by water through which the current passes, so that the efficiency of the heater depends on the characteristics of the volt per cm. curve.

It is well known that in electric steam generators having concentric electrodes, overloading causes momentary vaporization of the liquid close to the inner electrode, transforming the steam generator into an interrupter similar in principle to the Wehnelt and Simon interrupter.

If R represents the resistance of 1 cc. of

water, the output transformed into heat in 55 this volume of water is represented by the formula

$$\frac{\text{volts per cm}^2}{R}$$

The curve of watts per ccm. in Fig 1 represents this value where $R=1000$ ohms. The ratio of the output in ccm. at the inner electrode to the output at the outer electrode is equivalent to 25 to 1, that is, to the square 65 of the ratio of the radii.

The formation of steam bubbles further reduces the efficiency. The bubbles of course form in much greater quantity against the inner cylinder owing to the greater watts 70 per ccm. and by decreasing the cross-section involve increased current density and consequent increased voltage drop and decreased efficiency. For these reasons the concentric arrangement must not be run at too high a 75 load.

The present invention has for its object to overcome the drawbacks of the concentric arrangement and for this purpose the surface of the outer cylinder is made equal or 80 approximately equal to that of the inner cylinder so that the current density is the same at both electrodes. This may be effected by covering part of the surface of the outer electrode with insulation.

Fig. 2 shows one example in which a is the inner electrode b' , b^2 , b^3 and b^4 are the surfaces of the outer cylinder actually available to the current and equal in area to a . The rest of the surface of the outer cylinder 90 is covered with insulation c' , c^2 , c^3 , and c^4 . By this arrangement the current is distributed as indicated in dotted lines in Fig. 2. The curves for volts per cm. and watts per ccm. are also shown for a voltage difference of 500 volts with $r' = 1$ cm. and

$$\frac{r^2}{r'} = 5 \text{ cm.}$$

A comparison of the two diagrams shows 100 that the maximum value of watts per ccm. in Fig. 1 is only reached by the arrangement according to Fig. 2 with more than twice the main current voltage. Thus the arrangement according to Fig. 2 approxi- 105 mates the ideal condition in which the current is uniformly distributed over the space between the two electrodes.

In order to avoid a short circuiting effect on the current distribution, the base or ends of the boiler may be also covered with insulation.

5 Fig. 3 illustrates a constructional form of the heater, in which the bottom *e* is covered by insulation *f* and the tubular body *d* of the boiler is closed at the top by a cover *k*, and in which the inner electrode *a* is connected to a binding post *h* on the cover by a conducting rod *g*.

The insulation used for covering the surface of the electrodes also serves simultaneously to protect the boiler from the heat.

15 Claims:

1. An electrical liquid heater having concentric electrodes and insulation covering a part of the inner surface of the outer electrode to leave an uncovered outer electrode

surface equal or substantially equal to that 20 of the inner electrode.

2. An electric liquid heater as specified in claim 1 in which the insulation is in sections distributed uniformly around the inner electrode.

25 3. An electric liquid heater comprising a liquid container, concentric electrodes projecting thereinto, insulation covering part of the inner surface of the outer electrode so as to leave an uncovered outer electrode 30 surface equal or substantially equal to that of the inner electrode and insulation on the surface of the container for preventing a short-circuiting effect on the current distribution.

35 In testimony whereof, I hereunto affix my signature.

WILHELM PENZOLD.
